UNITED STATES PATENT OFFICE.

JOHN WOODVILLE, OF CINCINNATI, OHIO.

IMPROVEMENT IN CARPENTERS' PLANES.

Specification forming part of Letters Patent No. 59,498, dated November 6, 1866.

To all whom it may concern:

Be it known that I, JOHN WOODVILLE, of Cincinnati, in the county of Hamilton and State of Ohio, have invented a new and useful Improvement in Jointing-Planes; and I do hereby declare that the following is a full, clear, and exact description thereof, which will enable others skilled in the art to make and use the same, reference being had to the accompanying drawings, forming part of this specification, in which—

Figure 1 is a side view of a plane with my improvement attached. Fig. 2 is a cross-section of the same, taken through the line $x\ x$, Fig. 1. Fig. 3 is a detail sectional view of the same, taken through the line $y\ y$, Fig. 1.

Similar letters of reference indicate like parts.

My invention has for its object to furnish an improved jointing-plane, by means of which the edge of a board may be made square, or may be beveled at any desired angle; and it consists in the supporting angular plate, the adjustable hinged guide-plate, the adjusting-screw, bush-nut, wrench, and lock-nut, in combination with each other and with the stock or frame of the plane, when said parts are constructed and arranged as hereinafter more fully described.

A is the plane-stock, about the construction of which there is nothing new. B is the supporting-plate, which consists of three portions, b^1 , b^2 , and b^3 . The part b^1 is attached to the side of the plane-stock A by two bevel-headed screw-bolts, C and D, which pass through beveled slots E and F in the said part b^1 of the plate B, as shown in Fig. 1. The slots E and F are beveled in two ways: first, their edges are beveled so as to fit upon the beveled under side of the heads of the bolts C and D, as shown in Fig. 3; and, second, they are beveled or made wedge-shaped, so as to clamp the bolts C and D, and thus be held securely in place. The rear end of the slot E is enlarged, so as to permit the head of the bolt C to pass through it, but the slot F is cut through the edge of the plate, as shown in Fig. 1. The part b^2 stands at right angles to the part b^1 , as shown in Figs. 1 and 2. The part b^3 projects from the upper edge of the part b^2 , and is parallel with the part b^1 , as shown in Fig. 2. The

part b^3 is made in the form of an isosceles triangle, and has a hole made through its apex, which hole is countersunk or rounded out on its upper side, for the purpose hereinafter mentioned.

The plate B is strengthened by having a flange cast upon its edge, as shown in Figs. 1 and 2.

G is the sliding guide-plate, the side edges of which project downward, so as to form ribs or runners g^1 , upon which it slides along the surface of the timber being operated upon, and insures the plate G from rocking, and gives a steady movement to the plane. g^2 and g^3 are projecting ears or arms cast upon the plate G, by means of which said plate is pivoted to the plate B. The pivoting-point g^4 , attached to the ear g^3 , is made solid therewith; but the pivoting-point g^5 , attached to the ear g^2 , is removable, being the point of a screw passing through the said ear, as shown in Fig. 1. These points g^4 and g^5 enter and work in sockets formed in the edge of the part b^2 of the plate B, as shown in Fig. 1.

The ears g^2 and g^3 are made with a shoulder, as shown in Fig. 2, so that the inner edge of the plate G may be as low or a little lower than the upper corner of the edge of the plane-iron, so that the whole edge of the board may be smoothly cut.

g^6 are two ears, cast upon the upper surface of the plate G, between which the end of the screw H is pivoted by a pin passing through the said ears and the said end of the screw, as shown in Fig. 2.

I is a bush-nut, which passes up through the hole in the part b^3 of the plate B, before described, and through which the screw H passes. J is a wrench, which fits upon the upper end of the bush-nut I, and which has a feather formed upon its inner surface, which feather enters a slot or groove in the side of the said bush-nut I, so that the said nut may be raised or lowered by turning the wrench J. The nut I is made with a flange on its lower end, and the lower end of the wrench J is rounded off, so as to fit into rounded-out parts of the hole through the plate B at whatever angle the screw H may stand.

K is a lock-nut, which screws down upon the screw H, and locks the wrench J, plate B,

and bush-nut I firmly together, the plate B being clamped between wrench J and the flange of the nut I, as shown in Fig. 2.

Into the lower face of the nut K is cut a deep circular groove, as shown in Fig. 2, into the bottom of which is placed a rubber or other elastic spring, L. M is a metal ring, placed in the said groove upon the said spring L. When the nut K is screwed down upon the wrench J the end of the ring M comes in contact with the face of the said wrench J, and holds the parts with an equal pressure at whatever angle the screw H may stand.

By this construction and arrangement the guide-plate G may be set at any angle with the face of the plane, so as to give any desired

bevel to the jointed edge of the board operated upon, and the parts are all held firm and immovable while the plane is being used, thus insuring a perfectly true joint.

I claim as new and desire to secure by Letters Patent—

The hinged screw-rod H, in combination with the parts D G, and provided with the flanged nut I, wrench J, and lock-nut K, when arranged with the jointing-plane herein described, substantially as and for the purpose specified.

JOHN WOODVILLE.
